UNITED STATES PATENT OFFICE.

WILLIAM FRANCIS WILLIAMS, OF FISHGUARD, ENGLAND.

AUTOMATIC BOAT-RELEASER.

1,114,088.

Specification of Letters Patent. Patented Oct. 20, 1914.

Application filed April 25, 1914. Serial No. 834,526.

To all whom it may concern:

Be it known that I, WILLIAM FRANCIS WILLIAMS, a subject of the King of England, and resident of Fishguard, Pembroke-shire, England, have invented certain new and useful Improvements in Automatic Boat-Releasers, of which the following is a specification.

This invention is a contrivance to release 10 a boat automatically when the full weight of the boat has been taken off the ship's falls, (or such suspenders) by the water.

The shackles of the lower fall blocks are retained in engagement by spring-pressed 15 bolts which are withdrawn when the boat is water borne by an inextensible cord pulled by a spring set in tension by a lever, the pull of this latter spring being sufficient to overcome that of the other springs and 20 withdraw the bolts simultaneously.

The invention is described with reference to the accompanying drawings in which—

Figure 1 shows a plan of a boat fitted with my invention. Fig. 2 is a side elevation of 25 the hook engaging the shackle of the lower fall-block. Fig. 3 is a side elevation of the levered spring device under the central thwart (the handle being above the thwart) or the thwart farthest aft.

30 A is a bolt, the lower part of an iron rod traveling through the holes D and E and bent at eyelet hole G.

B is a bolt, the upper part of the same iron rod traveling through the holes C, and 35 F backward and forward in the same direction as bolt A. The use of A is to keep the bolt B in position with the aid of the spring Q. Bolt A is made that much longer than bolt B, so as to allow B to be drawn back 40 till the end of B is in the hole F, before the locknuts J press the spring Q, against the hole D. Bolt B is also long enough to retain a hold on hole C when not drawn back. The use of bolt B is to act as a shackle-bolt 45 to secure the boat to the links or shackles of the lower pulleys of davits'-falls, when the bolt is not drawn back.

S, and T, and U, and M, and N and Z is a plate of iron shaped in such a manner so 50 as to be a frame with holes in it to allow bolts A and B to travel backward and forward in the same direction as described. There is also a threaded hole in the T-part of the frame, viz. the lower part of the

frame, so as to admit the frame to be 55 screwed fast to the iron rod O (that goes down to the boat's keel) and locked with the nut R, or riveted.

N is the continuation of M; the part Z of the frame has also a continuation the 60 same as N (see Fig. 1).

H is a space cut between Z and M and also between their continuations to act as a guide to the bolt B to enter the hole F when the boat is to be secured to the links or 65 shackles of the lower pulleys of davits'-falls. The space H is made large enough to allow the bolt B to move backward and forward freely.

The use of locknuts J is that they are 70 locked in a position on bolt A, so as to press the spring Q against the hole D immediately the bolt B has passed the hole F when the bolts A and B are drawn back for releasing the boat.

75 W is the threaded end of bolt A. The flat spring Q has got a hole at the upper end, big enough to allow the spring Q to make the arc of a circle, without the edges of the hole, pressing against the bolt A. 80 The lower end of the flat spring Q is secured by a grip to the iron rod O that goes down through the boat to the boat's keel. The grip is provided with locknuts L and washer K to secure the lower part of the 85 flat spring Q to the rod O.

50 is a screw adjuster, it has a hook to hook on to the eyelet hole G, it also has a locknut to lock it when it is screwed up to adjust the tension of the wire rope 7; it 90 has also a swivel to allow the rope to be tensioned without twisting it (rope). The swivel part of the adjuster has got a hole 6 to fasten the wire rope 7 to the adjuster; one end of the iron that forms part of the 95 frame of the adjuster and locked with a nut.

The lever device shown in Fig. 3 is connected by connecting links 36, that are attached to wire rope 7 that leads through 100 fairlead pulleys to the screw adjuster 50, that is hooked on to the hook shown in Fig. 2 that is placed at the bow, and another of the same kind placed at the stern of a boat.

The lever device shown in Fig. 3, is a 105 frame of a triangular shape made of pieces of iron 14, and 15, and 16; these pieces of iron are riveted together and fitted with the

iron rod 33, that is fastened to spring 25, that is hooked on to the hook 21 (see Fig. 1) that is screwed into lever 11, that is screwed to the lug 35 of the triangular frame, with the threaded pin 8 locked with a nut.

The iron 14, and iron 15, and iron 16 are riveted together with rivets 22, and 23, and 10 in such a manner as to allow the lever 11 to be placed from one top corner of the frame to the other top corner of the frame. The member 16 of the triangular frame has a bend at both ends; and is provided with a catch 24 to hold the lever 11 when the strain is put on the spring to draw back the bolt B, of Fig. 2. The member 16 has also holes 18 and 19; the use of hole 18 is to admit the end of a marlinespike, or something similar to pass through it to hold the lever 11 in position when the apparatus 20 is getting adjusted. The use of hole 19 is also to admit the end of a marlinespike to pass through it to hold lever 11 in position; that is, should the spring 25 at any time exceed the required strength that is necessary to adjust the apparatus when the lever is set at hole 18. The member 15 of the triangular frame is provided with a lug 30 at the top end, screws pass through the lug into the underside of the boat's thwart to 30 secure the frame in position, the member 14 of the triangular frame is provided with a lug 27 at the top end of it, screws pass through the lug to secure the frame in position. The member 14 of the triangular frame is also provided with a lug 35 at the bottom end to secure the lower end of lever 11, by the means of passing a threaded pin 8 through a hole in the lever and screwing the pin into the lug 35, and lock the pin 40 with a nut, as stated. The lever 11 has got a handle 17 for the operator to catch hold of when the lever is to be drawn back to the catch 24, or freed from catch 24; the lever is also provided with the threaded hole 20; the hook 21 is screwed into the hole 20 (and locked with a nut) below the upper edge of the member 16 of the triangular frame, when the lever 11 is in the middle. The hook 21 is curved at the hooking end of it

so as to avoid the spring 25 from slipping off when no weight is on the spring 25.

The iron rod 33 is provided with the hole 26, to which one end of the spring 25 is secured; the iron rod 33 is also provided with a hole 32 of an oblong shape, big enough to link on to it the connecting links 36 free of each other. The iron rod 33 is provided with guides 31, and 34 so that the rod 33, and spring 25 will not go down from the thwart when no weight is on the spring 25. Guides 31, and 34 for the rod 33 are placed under the thwart so as to allow the rod 33 pass backward, and forward sufficiently for the bolt B of Fig. 2 to answer its purpose, viz. to secure the boat to the falls and release the boat when required.

The connecting links 36 are engaged so that when the wire ropes 7 have stretched, the connection between the bolt B and the lever 11 can be shortened by the connecting links, and adjusted by the adjuster 50. The wire rope 7 leads straight in the middle of the beat from adjuster 50 to a fairlead pulley (that is placed at a sufficient distance from adjuster 50 so that the adjuster 50 will not touch the pulley when the lever 11 is placed at the catch 24) then the wire rope is led at a right angle to a pulley at the boat's side and thence along the inner side of the boat's side through fair-lead stables (to keep the wire rope close to the side clear of the cargo) to the rollers 51 and through the rollers to the links 36.

What I claim, is:—

A boat releasing gear, comprising in combination, shackles of the lower blocks of the falls, spring-pressed bolts engaged by said shackles, cords to withdraw said bolts upon the boat being water-borne, a spring connected with said cords, and a lever to set the spring in tension for a withdrawal of the bolts, substantially as and for the purpose set forth.

WILLIAM FRANCIS WILLIAMS.
